UNITED STATES PATENT OFFICE.

ALEY E. JONES, OF CUYAHOGA FALLS, OHIO, ASSIGNOR TO LAMBERT TIRE & RUBBER CO., OF BARBERTON, OHIO, A CORPORATION OF ARIZONA.

DESIGN FOR A TIRE.

Application filed March 27, 1928. Serial No. 26,030. Term of patent 14 years.

To all whom it may concern:

Be it known that I, ALEY E. JONES, a citizen of the United States, residing at Cuyahoga Falls, in the county of Summit and State of Ohio, have invented a new, original, and ornamental Design for Tires, of which the following is a specification, reference being had to the accompanying drawing, forming a part thereof.

I claim:

The ornamental design for a tire substantially as shown.

ALEY E. JONES.
